7 Claims. (Cl. 28—43)

The present invention relates to a machine for separating the outside thread of a warp from the other warp threads.

Mechanisms are known for separating the outside thread of a warp and presenting the separated warp thread to a tying machine. These mechanisms are provided with a feeler which forms part of an apparatus for stopping the mechanism, if no thread has been separated. The Swiss Patent No. 139,632 shows a mechanism which is stopped only after the thread separating movement has been repeated several times without separating a thread. In this way the machine is stopped much less frequently than a machine which is stopped every time the separating mechanism fails to separate a thread. It happens quite often that, after several repetitions of the thread separating movement, a thread is separated so that, for example, the tying apparatus can continue to operate. The aforescribed provision of several idle movements of the thread separating device before the machine is stopped has the disadvantage that the idle movements are performed under the same conditions, particularly at the same speed. It has been found that if the speed of the thread separating machine is reduced there is a greater probability that a thread is caught and separated than if the machine continues to operate at the same speed.

It is an object of the present invention to provide a warp thread separating machine which continues to operate an adjustable predetermined number of times when no thread is separated and in which the speed of operation of the machine is progressively reduced as the number of idle operations increases. The mechanism according to the invention may be provided with means for adjusting the initial or basic speed of operation of the machine which speed is reduced, if no thread is separated. Additionally, the machine may be provided with a device which indicates whether the machine has performed an even number or an odd number of idle operations during which no thread was separated.

The novel features which are considered characteristic of the invention are set forth with particularity in the appended claims. The invention itself, however, and additional objects and advantages thereof will best be understood from the following description of an embodiment thereof when read in connection with the accompanying drawing the one figure of which diagrammatically illustrates, by way of example, a mechanism according to the invention.

Referring more particularly to the drawing, numeral 1 designates an outside thread of a warp 2 which thread is separated from the warp by means of a conventional needle 3 upon downward movement of the latter. The needle 3 is moved up and down by means of a lever 4 which is connected for oscillation with a driving motor 50 by conventional means indicated by a dash-dot line and not shown in detail. In the illustrated embodiment of the invention, the thread 1 is taken over by a hook at the end of an element 5 and moved to the right for

2

presentation, for example, to a tying mechanism, not shown.

The element 5 is movable relative to a T-shaped element 6 with which it is connected by a spring 7 which urges the elements to move towards each other. This movement is limited by a pin 8 mounted on the element 5. The assembly 5, 6, 7 is guided to move on a straight line by a stationary pin 9 extending into a slot 10 in the element 5 and by a stationary guide 11 which slidably guides the element 6. The latter is reciprocated by a crank 12 to which it is connected by a rod 13. The crank 12 is driven by the motor 50 through means, indicated by a dash-dot line and not shown in detail. Since the element 6 is connected with the element 5 by the spring 7 the element 5 is reciprocated with the element 6, pulling the weft thread 1, which has been pushed downward by the needle 3, to the right and against an arm of an elbow lever 14. The latter is thereby swung counterclockwise against the action of a spring 15 from a rest position defined by a stationary pin 16. The end of the free arm of the lever 14 is provided with a catch 17 cooperating with a nose 18 on the element 5. The catch 17 is moved out of the way of the nose 18 when the lever 14 is swung counterclockwise so that the element 5 can follow the movements of the element 6 whereby the pin 8 abuts against the element 6. If no weft thread 1 is seized by the needle 3, the lever 14 remains in the illustrated position whereby the nose 18 abuts against the catch 17 and the element 5 is stopped after a short movement to the right, while the element 6 continues to move to the right, tensioning the spring 7 and moving away from the pin or abutment 8.

As long as the thread separating mechanism operates orderly the relative position of the elements 5 and 6 is not changed and an extension 22 of a pawl 19 swingable on a pin 20 which is mounted on the element 6 is pressed against an abutment 23 on the element 5 by means of a spring 21. The result is that the pawl performs a true translatory movement only and does not engage a ratchet wheel 24. If the thread separating device fails to separate a thread, the element 6 and the pawl 19 move away from the abutment 23 so that the pawl can move counterclockwise due to the action of the spring 21 and engage the ratchet wheel 24 and, upon continued movement of the element 6 to the right, shifts the ratchet wheel by one tooth. The ratchet wheel 24 rotates on a shaft 25 and is rigidly connected with a disc 29 provided with an abutment 30. A spiral spring 28, having an end connected to a pin 27 mounted on the ratchet wheel and the other end connected by a pin 26 to a toothed wheel 32 which is rotatable on the shaft 25, tends to rotate the ratchet wheel 24 in clockwise direction. A pawl 34 prevents clockwise rotation of the wheel 24 so that the ratchet wheel is rotated counterclockwise by one tooth at each movement of the pawl 19 to the right.

When the thread separating mechanism functions normally the element 5 moves with the element 6 and a nose 35 on the former engages an extension of the pawl 34, disengaging the latter from the ratchet wheel against the action of a spring 36. Since, at the same time, the pawl 19 is disengaged from the ratchet wheel, the spring 28 can turn the ratchet wheel clockwise until the abutment 30 abuts a pin 31 mounted on the wheel or disc 32. If the latter is turned, after release of a latch 37 against the action of a spring 38, the initial position of the wheel 24 can be changed as desired.

The abutment 30 engages a pin 39 after a predetermined number of idle strokes of the needle 3, when the latter fails to separate a thread whereby this number of idle strokes depends on the position of the wheel 32 with the abutment 31. Engagement of the pin 39 by

the abutment 30 effects stopping of the motor 50 in a manner which will be described later.

The mechanism described so far is conventional and affords selection and adjustment of the number of idle strokes of the thread separating needle which are needed for stopping the machine.

In the machine according to the invention a toothed wheel 40 is coaxially mounted on the ratchet wheel 24, the teeth of the wheel 40 being in mesh with teeth of a rack rod 41. The latter is guided to move in axial direction by guides 42 and 43. The upper part of the rack rod 41 is threaded and carries a nut 44 which can be locked in a desired position by a lock-nut 45. The nut 44 is provided with a pin 46 extending into a slot 47 of a lever 48 whose free end is rigidly connected with a brush support element 49 of the electric repulsion motor 50. When the ratchet wheel 24 with the toothed wheel 40 are in the initial position, i.e. in the position in which they are as long as the machine operates normally, the initial speed of the motor 50 can be adjusted by adjusting the position of the nut 44 on the rod 41. If the machine fails to separate a warp thread, the toothed wheel 40 step-wisely moves the rod 41 and the lever 48 into positions corresponding to reduced speeds of the motor 50. The thread separating operation is, therefore, performed under more favorable conditions. If, after a certain number of idle strokes of the needle 3, a thread is caught and separated, the ratchet wheel is returned by the spring 28 into an initial position which is defined by the position of the disc 32 and the pin 31. Simultaneously, the rod 41 is moved downward and the motor 50 operates again at its initially adjusted relatively high speed.

If, due to unfavorable circumstances, no thread is separated after a predetermined number of idle operations of the needle 3, the abutment 30 engages the pin 39 and moves it to the left. A lever 51 having an arm pivoted to the pin 39 is thereby swung in clockwise direction against the action of the spring 36. A hook 52 at the end of an arm of the lever 51 is thereby pulled out of a corresponding recess in a bolt 54 which can now move upward due to the action of a spring 53. This upward movement releases the bolt 54 from a switch 55 which is opened thereby. The switch 55 controls the operation of the motor 50, stopping the motor when the spring is opened, by conventional means indicated by a dotted line.

When the mechanism is in normal operating position, the motor can be started by depressing the bolt 54 against the action of the spring 53 and closing the switch 55. Since the hook 52 retains the bolt in the depressed position, the motor continues to operate. If, after a predetermined number of idle strokes of the pin 3, the hook 52 is disengaged from the bolt 54, only a continued manual depression of the bolt 54 will keep the motor 50 in operation. This is of advantage, because in some cases it is desirable to operate the motor in spite of an irregularity in the thread separating operation. On the other hand, the motor can be stopped, even if the machine operates normally, by manually turning the lever 51 in clockwise direction.

In tying machines in which the threads of the used up warp must be connected to the threads of the new warp two weft separating mechanisms are mirror-symmetrically arranged. In order to recognize double threads in leased warps it is of advantage to be able to ascertain immediately whether the number of idle movements of the separating needle is odd or even. For this purpose a pawl 57 is pivoted at 56 to the element 6. A spring 58 tends to swing the pawl 57 in clockwise direction until an extension 59 of the pawl abuts a pin 60 which is mounted on the element 5. The pawl 57 is adapted to engage a ratchet wheel 61 in the same manner as the pawl 19 engages the ratchet wheel 24, i.e., the ratchet wheel 61 is not engaged as long as the machine operates normally and the ratchet wheel is moved by one tooth at each idle stroke of the needle 3. Reverse movement of the ratchet

wheel 61 is prevented by a pawl 62 which is swingable on a pin 63 and urged in clockwise direction toward the ratchet wheel by means of a spring 64. A toothed wheel 65 is coaxially connected to the wheel 61. The teeth of the wheel 65 are so shaped that each gap 66 between two teeth corresponds to two teeth of the ratchet wheel 61. A pin 67 is urged against the wheel 65 by means of a spring 68 and has a free end adapted to be received in the gaps between the teeth of the wheel 65 and to slidably engage the tooth flanks. The tooth flanks defining a gap and the free end of the pin 67 are so shaped that the pin 67 moves the wheel 65 counterclockwise by pressing against one flank until the other flank rests on the side of the pin 67, preventing rotation of the wheel 65. The pin 67 is in the left position, shown in solid lines, after an even number of idle movements of the thread separating mechanism and is in the right position, shown in dash-dot lines in the drawing, after an odd number of idle movements. The position of the pin 67 instantly indicates odd numbers and even numbers of idle movements of the weft thread separating machine.

I claim:

1. In a machine for separating the outside warp thread of a warp, including drive means for driving the machine, a member connected to and driven by said drive means for periodically moving towards the warp thread to be separated and, upon engagement with the warp thread, moving the warp thread away from the other warp threads, a feeler adapted to be engaged by a separated warp thread, means for stopping said drive means, and a mechanism operatively associated with said stopping means and with said feeler and including means for actuating said stopping means to stop said drive means after a predetermined number of idle movements of said member during which said member fails to engage a warp thread; wherein said mechanism includes means for reducing the speed of drive of said drive means with increasing numbers of idle movements of said member.

2. In a machine as defined in claim 1 and wherein said mechanism includes adjusting means for adjusting the number of idle movements of said member, after which said actuating means actuates said stopping means for stopping said drive means.

3. In a machine as defined in claim 1 and wherein said means for reducing the speed of drive of said drive means includes setting means for setting the initial speed of drive of said drive means which is the speed of said drive means before the speed is reduced by an idle movement of said member.

4. In a machine as defined in claim 1 and wherein said mechanism includes two movable elements, yielding means interconnecting said elements and permitting relative movement of said elements, the first of said elements being connected with said drive means for periodically moving said elements, the second of said elements being engaged and held stationary by said feeler when the latter fails to engage a warp thread, and means connected with the first of said elements for engaging said actuating means when said first element is moved by said drive means relatively to the stationary second element against the action of said yielding means.

5. In a machine according to claim 4 and wherein said mechanism includes means for returning, upon disengagement of said feeler from said second element, said mechanism to its initial position in which said mechanism was prior to the first idle movement of said member.

6. In a machine as defined in claim 1 and wherein said means for actuating said stopping means includes a locking member, a spring connected with said locking member and urging said locking member into unlocking position for effecting actuation of said stopping means, and a latch adapted to engage said locking member for holding it against the action of said spring in locking position for preventing actuation of said stopping means,

said mechanism including means engaging said latch member and disengaging the latter from said locking member for effecting actuation of said stopping means.

7. In a machine as defined in claim 1 a device operatively associated with said mechanism for indicating odd 5

numbers and even numbers of idle movements of said member.
